(57) **CLAIM**

The ornamental design for a flashlight, as shown and described.

DESCRIPTION

FIG. 1 is an isometric view of a flashlight design according to the present invention;

FIGS. 2 and 3 are side views of the flashlight of FIG. 1;

FIG. 4 is a top view of the flashlight of FIG. 1;

FIG. 5 is a bottom view of the flashlight of FIG. 1;

FIGS. 6 and 7 are end views of the flashlight of FIG. 1;

FIG. 8 is an isometric view of a flashlight design according to the present invention having side, bottom and end views as shown in FIGS. 2-3 and 5-7;

FIG. 9 is a top view of the flashlight of FIG. 8; and,

FIGS. 10 and 11 are end views of the flashlight of FIG. 8.

Broken lines in the illustrations of FIGS. 1-11 of the drawing indicate parts of the article that are not part of the design sought to be patented. Although the views are denominated as side, top, bottom and end, the flashlight may be held or placed in any orientation, and the claim is not limited by such denominations.
